UNITED STATES PATENT OFFICE

2,211,999

PROCESS FOR HYDROCARBON OIL
CONVERSION

Joseph G. Alther, Chicago, Ill., assignor to Universal Oil Products Company, Chicago, Ill., a corporation of Delaware

Application November 30, 1936, Serial No. 113,427

3 Claims. (Cl. 196—60)

This is a continuation-in-part of my co-pending application Serial No. 355,704 filed April 17, 1929, now Patent No. 2,091,261.

This invention relates to improvements in process for hydrocarbon oil conversion, and refers more particularly to improvements designed for the efficient cracking of hydrocarbon oils to convert and produce therefrom products having higher commercial value.

16 The utility of the invention as well as many objects and advantages thereof will be brought out in the following description.

The principal object of the invention is to subject hydrocarbon oil to such conditions of 18 temperature and pressure as to produce maximum yields of lighter gravity products suitable for use as motor fuel with a minimum coke and gas loss.

Another object is to carry out the operation 20 in such manner as to cause the non-vaporous residue to accumulate in a low pressure zone.

Another object is to provide in a cracking process and apparatus steps and means whereby it is possible to approach dry distillation.

25 In one type of operation practised commercially on a large scale, the conditions of operation are so controlled as to mainly produce a gasoline-like product suitable for use as motor fuel, which is the desired product of conversion, and a substantially solid coke-like residue. Such operation is described as a "non-residuum" type of 30 operation, the expression "residuum" in such instance meaning liquid. The operation is carried out in a tube and drum type of apparatus 35 wherein the oil is heated in the tube and discharged into the drum where separation takes place between the lighter and heavier products of conversion, both the tube and drum being maintained under substantially superatmospheric 40 pressure.

In a conventional non-residuum type of operation it is possible to approach dry distillation, accomplishing same in the drum, wherein practically all volatile matter is distilled off, leaving a substantially solid, coke-like residue. One of the reasons why this is possible in the non-residuum type of operation is the large amount of cracking time given to the heavy material in the pressure drum whereby it is reduced to a coke solid. Obviously this could not be done except for the fact that a large amount of heat is constantly supplied to the drum by the incoming oil to carry on this reducing or coking action.

45 As is well known, such type of operation produces a maximum amount of coke, due to crack-

ing and polymerization of the cracked materials in the pressure drum, thereby decreasing the actual onstream time efficiency of the system. To eliminate the objectionably large coke production, it has become common practice, in many cases, to remove the liquid residue from the pressure drum, reduce or release its pressure and discharge same into what is termed a "flashing still," which in reality takes the form of an unheated drum or still operating under little or no 10 pressure. A flashing operation has advantages as well as disadvantages, one of the advantages being a long time onstream before shutting down. Some of the disadvantages are a somewhat reduced gasoline yield as compared to non- 15 residuum operations and large amounts of liquid residue or fuel oil which may be unmarketable in some instances because of high viscosity and/or other objectionable characteristics. As a matter of fact the final liquid residue or flashed 20 residuum which is withdrawn from the flashing still resembles a product which is uncracked. I do not mean to indicate that this oil is not cracked but merely that it resembles an uncracked oil. This may be due to a polymerization, or it may be the direct result of decreasing the time to which residue is normally subjected to cracking as compared with a non-residuum 25 type of operation. Or, the high viscosity of the final flashed residue may also be due to other 30 causes which need not be here analyzed.

It has been determined that, in a non-residuum 35 type of operation, there is practically a complete distillation, that is, all or substantially all of the volatile matter is removed from the pressure drum through the vapor line and what remains in the chamber is substantially a solid. The flashing operation is different—a relatively lower percentage of the oil leaving the pressure drum leaves that drum through the vapor line in the 40 form of vapors. A greater proportion of the oil is withdrawn from the bottom of the pressure drum and flashed into the reduced pressure 45 flashing still where, due to the pressure reduction, latent heat contained in the oil is liberated and utilized to carry on the distillation of this oil.

From the foregoing it will be apparent that there is a pressure distillation and separation in the pressure drum and a second distillation and separation in the reduced pressure flashing still.

The purpose of the present invention is to embody in an efficient process and apparatus the desirable features of both the non-residuum and flashing types of operation, the conditions being 55

so controlled in the flashing still as to produce either a good liquid or semi-liquid residue suitable for example as fuel oil or asphalt making stock, or coke of controlled volatility, as local 5 conditions may dictate.

The charging stock plus reflux will be pumped through a conventional furnace having a relatively large heating surface or tubular cracking coil from which the heated oil may be transferred to a drum or high pressure reaction chamber. This drum may be unheated but lagged against excessive radiation losses. The oil in the coil and the drum is maintained under superatmospheric pressure ranging from 100 to 1000 10 pounds, more or less. Expansion takes place in the drum from which substantially all oil, vapor and gas may be withdrawn through a single outlet being directed into a large flash drum where flash distillation takes place by reduction in pressure. In certain operations where insufficient 15 heat is contained in the residual oil leaving the high pressure drum, additional heat may be supplied to the oil either prior or subsequent to its introduction into the flash chamber, or both.

Vapors from the flashing still are directed to a 20 dephlegmator where the low boiling, sufficiently converted fractions are separated from the higher boiling, insufficiently converted fractions, the latter being condensed as reflux condensate by 25 the incoming cold raw oil or other cooling medium, and said reflux being returned to the cracking coil for retreatment.

A feature of the invention is to have the oil 30 which is undergoing treatment in cracking stage at such temperature and pressure that, when the oil is released in the flashing still, there will be sufficient heat to give rapid and substantially complete distillation to dryness, that is, separation of substantially all of the vaporizable constituents from the oil, removal of the same from the flashing zone and accumulation of substantially solid residue in the latter.

In order to more clearly understand the invention, I have shown the accompanying drawing, 35 which is a diagrammatic view, but not to scale, of an apparatus suitable for conducting the process of the invention.

Referring to the drawing and to the operation 40 of the process, the oil to be treated is directed through line 1 having valve 3 into a heating coil 4, located in a conventional furnace 5.

Raw oil to be treated in the process may be drawn from suitable storage tanks (not shown) through line 43 and pump 44. From line 43 and 45 by suitable control of the valves shown, all or a portion of the raw oil to be treated in the process may be diverted through line 45 and valve 46 to line 47 which connects with the main feed line 1, whereby all or any desired portion of the charging stock may be fed directly to the heating tubes, 50 preferably mixing before entering therein with reflux condensate supplied to line 47, as herein-after described.

In heating coil 4 the oil is heated to a temperature within the cracking range under a suitable pressure. The amount of oil passed through the coil per unit time, and the size of the apparatus are so correlated that under the temperatures and pressures used the degree of cracking 55 obtained in the heating coil is preferably short of that at which formation of coke and sludge-like matter occurs, or exceeds a predetermined unobjectionable amount.

Chamber 10 to which the heated products from 60 coil 4 are supplied through line 6 and valve 7 may

take any desired form and size in relation to the capacity of the apparatus. It may be unheated and insulated against loss of heat by radiation. It is to be understood that the preferred method of operation is of the low level type, wherein a minimum quantity of residual oil is maintained in the chamber 10. That is, residual oil is withdrawn from chamber 10 before it has had sufficient time to form more than five percent or thereabouts of sludge or coke-like constituents. 10

I have discovered that when the degree of conversion obtained in the cracking zone, such as heating coil 4 and chamber 10, is so controlled that the heavier liquid products separated there-in do not contain more than generally five percent and preferably less than 2 percent, of sludge-like or coke-like materials, as may be determined by so-called benzol centrifuge method, said heavier liquid products contain a substantial proportion of vaporizable fractions, which, when separated from such solids or sludge-like materials under proper conditions, may be subjected advantageously to additional cracking for the formation of substantial additional yields of motor fuel. This may be effected by regulating the conditions in coil 4 and chamber 10, or by subjecting the heavy liquid products withdrawn from chamber 10 to such additional treatment, as will hereinafter be described, that a so-called dry distillation thereof is effected, leaving in the zone of distillation a substantially solid residue, the remaining fractions having been vaporized to produce a material which may be advantageously subjected to additional cracking. 20

Two methods of operation are contemplated. 30 In the first method, both the vaporous and unvaporized oil will be withdrawn through line 51 from the bottom of chamber 10, and passed through valve 52, wherein the pressure is reduced, to flash chamber 54. The advantage of this procedure, especially with non-residuum operations, will be that an appreciable partial pressure effect will be exerted by the vapors, tending to increase the amount of vaporization in the flash chamber and decrease the amount of unvaporized fractions remaining therein. In the second method 40 of operation, vapors will be separated and withdrawn through vapor line 19, while the residual oil will be withdrawn from the bottom of the chamber through line 51. 50

As a feature of the invention I may subject all or part of the vapors removed from chamber 10 to additional heating at elevated temperatures to effect a controlled degree of so-called "vapor-phase" cracking whereby I am enabled to produce 55 lighter valuable distillates having the characteristics of motor fuels or gasoline and possessing high anti-knock properties due to the presence of fairly large proportions of aromatic and unsaturated hydrocarbons formed by said vapor 60 cracking.

For this purpose vapor coil 22 may be positioned in furnace 5 and located therein in such a manner that the combustion gases pass over coil 22 before passing over coil 4. In this manner 65 the combustion gases passing over coil 22 may be higher in temperature than when they pass over coil 4 and a greater degree of radiant heat may be utilized in coil 22 than in coil 4. Coil 22 may be connected to vapor line 19 through 70 branches 23 and 24, respectively, controlled by valves 25 and 26. By proper regulation of valves 20, 25 and 26, any desired portion or all of vapors separated in chamber 10 may be passed through the vapor heating coil 22. 75

Provision is made to permit bleeding off of a regulated quantity of vapors from line 19 into line 100 by proper regulation of valve 101. By controlling the point of entry by means of valves 57, these vapors may enter flash chamber 54 either above or below the liquid level maintained therein. If full advantage of partial pressure effect of these vapors is to be taken, they should enter a low point in chamber 54 in order to obtain contact with the non-vaporous material therein, increase vaporization and facilitate reduction of the percentage of unvaporized oil.

Provision is also made for diverting, when desired, a regulated portion or all of the vapors withdrawn from chamber 10 from line 19 through line 100' and valve 101' to separate fractionating, condensing and collecting equipment, of any well known form, not illustrated.

By means of the reduction in pressure obtained by proper control of valves shown, a large portion of said unvaporized liquid products may be vaporized in chamber 54. Depending upon the conditions under which the operation is conducted and upon the characteristics of the charging stock employed, such reduction in pressure may be sufficient to distill or vaporize said heavier liquid products substantially to dryness by means of the self-contained heat in the heavy oil removed from chamber 10. However, I have found that generally this self-contained heat is not sufficient to induce satisfactory coking of the oil and in a majority of cases it is necessary to supply additional heat to the heavy liquid products withdrawn from the reaction zone either before subjecting them to flash distillation or during flash distillation thereof in order to vaporize substantially all of their volatile constituents and reduce the oil to coke.

One of the principal features of this invention resides in depositing the bulk of the carbon or coke outside the zone of high pressure. This permits the use of much cheaper equipment and minimizes the danger of explosion.

As a means of facilitating the operation for the production of substantially dry coke, a portion of the non-condensable gas from receiver 77 may be returned to vapor line 19 leaving reaction chamber 10 by means of valve 92 and pump 94 in line 93. This gas will pass through coil 22, either alone or together with the vapors from the reaction chamber, or may by-pass coil 22 through valve 20, depending upon the operation desired. In either event, by controlling valves 57 on flash chamber 54 the uncondensed gas, either alone or together with the vapors may be introduced at any one or more of several points therein either in highly heated state or otherwise, as desired. In the event the liquid level in chamber 54 is above any one of these points the hot gas and vapors will act as a partial pressure agent to facilitate vaporization and promote the coking operation.

It may be desirable to regulate the heating of the heavy liquid products supplied from chamber 10 to chamber 22 in such a manner that, while they receive the necessary additional heat to cause their substantially further vaporization by accompanying or subsequent reduction of pressure, the additional heat is not sufficient to cause substantial additional cracking to take place in the low pressure zone thereby decreasing the formation of the sludge and coke-like constituents.

Chamber 54 is provided with bottom draw-off line 61, having valve 62, whereby liquid or semi-liquid products may be removed therefrom. Coke

formed in the operation of the process and deposited in chamber 54 may be removed therefrom through top or bottom manholes in the usual manner.

Vapors separated by flash distillation in chamber 54 may be removed therefrom through line 66 having valve 67, and may be passed directly to condensing and collecting means, not shown, wherefrom the resultant products may be removed, all or in part, from the process or returned, in part, to the heating zone for retreatment. Or, as shown in the drawing, they may be passed first through a fractionating column 69, wherein they are subjected to controlled partial condensation for the formation of reflux condensate by introducing a suitable cooling and refluxing medium to dephlegmator 69 through line 70, having valve 71; or raw oil charged to the process may be diverted from line 43 through line 72, having valve 73 and introduced to column 69 to serve as a cooling and refluxing medium.

Vapors remaining uncondensed in column 69 may be removed therefrom through upper draw-off line 74, having valve 75, and passed through condenser 76 to receiver 77 which has the usual gas release valve 78 and distillate release valve 79. The fractions of the vapors condensed in column 69, comprising reflux condensate, may be discharged from the bottom thereof through line 80, in which may be interposed pump 81, from which this material may be passed through line 84 and valve 85 to feed line 47, whereby said fractions may be returned directly to heating coil 4.

While I have indicated a specific form of apparatus, in a diagrammatic manner, for the various parts of the system, it is to be understood that many other forms of apparatus and types of construction may be employed providing that the substituted equipment perform substantially the same function and obtain the desired results. For instance, a vapor phase cracking chamber, suitably heated, may be substituted for the vapor heating coil 22. A so-called soaking coil, or digestion chamber, may be substituted for the chamber 10 but if such is used it is preferably connected with a separating chamber, which may be unheated, such soaking coil (or digestion chamber) and the separating chamber performing the functions of the chamber 10 as herein shown and described. As another modification it may be desirable to interpose in line 24, connected with the discharge of the vapor coil 22 or its equivalent, a separator whereby heavy products of cracking and/or polymerization formed by the vapor cracking zone, may be separated from the vapors.

While I have described a particular arrangement of the various heating coils and a particular construction of the furnace 5, it is within the scope of the invention to use other relative arrangements of these parts providing that such alternative arrangement permits the operator to conduct the process in the manner and for the purpose indicated. For instance, each of the heating coils 4 and 22 may be positioned in separate furnaces, or coils 4 and 22 or their equivalents may be positioned in separate heating chambers of the same furnace wherein, in addition to, or independent of, the heat which may be produced by fuel from burners, the products of combustion which leave heating zones at relatively high temperatures may be utilized, all or in part, to heat the parts maintained at lower temperatures. For instance, the spent combustion gases leaving the zone wherein heating coil 4 may be positioned,

may be utilized to help heat coil 10. Any other combination may be employed to best utilize the heat of the process without departing from the scope of the invention so long as the desired relative temperatures, pressures and rates of heating may be obtained in the various steps of the process.

The operating conditions employed to accomplish the objects of the invention in an apparatus such as illustrated and above described may be approximately as follows: The first mentioned heating coil may utilize a conversion temperature ranging, for example, from 850 to 975° F., preferably with a superatmospheric pressure, measured 10 at the outlet therefrom, of from 100 to 500 pounds, or more, per sq. in. Substantially the same or a somewhat lower superatmospheric pressure may be maintained in the succeeding reaction chamber. The second mentioned heating 15 coil, to which vaporous products from the reaction chamber or uncondensed gaseous products of the process, or both, may be supplied, preferably employs a substantially higher temperature than that of the residual liquid products 20 withdrawn from the reaction chamber ranging, for example, from 850 to 1100° F., and the pressure employed in this zone may range from substantially the same as that maintained in the reaction chamber down to substantially atmospheric 25 pressure. The pressure employed in the vaporizing or coking chamber may range from substantially the same as that employed at the outlet from the second mentioned heating coil down to substantially atmospheric pressure and this zone 30 is preferably operated at a substantially reduced pressure relative to that employed in the reaction chamber. The fractionating condensing and collecting equipment to which vaporous products from the vaporizing or coking chamber are supplied 35 may utilize substantially the same or somewhat lower pressures than that maintained in the vaporizing or coking chamber.

As an example of one specific operation of the process, which may be conducted in accordance 40 with the provisions of the invention and in an apparatus such as illustrated and above described, the charging stock, which is a mixed base topped crude of approximately 26° A. P. I. gravity, is subjected, together with reflux condensate from 45 the fractionator, to a temperature measured at the outlet from the first heating coil of approximately 940° F. at a superatmospheric pressure of approximately 350 pounds per sq. in. Substantially the same pressure is maintained in the 50 reaction chamber from which vaporous and liquid products are withdrawn in commingled state and supplied to the coking chamber which is maintained at a superatmospheric pressure of approximately 50 pounds per sq. in. The liquid products 55 are reduced in this zone to substantially dry coke by the introduction, into direct contact therewith, of a portion of the uncondensed gaseous products of the process, heated in the second heating coil to a temperature of approximately 970° F. at a 60 superatmospheric pressure of about 100 pounds per sq. in. This operation will produce, per barrel, of charging stock, approximately 60 percent of 400° F. end-point gasoline having an octane number of approximately 67 and about 75 pounds 65 of good quality low volatile coke, the remainder being chargeable, principally, to uncondensable gas.

As a modification of the operation above described wherein vaporous and liquid conversion 70 products are separately withdrawn from the re-

action chamber, the latter supplied to the coking chamber and the vaporous products subjected in the second heating coil to an outlet conversion temperature of approximately 960° F. at a superatmospheric pressure of approximately 500 pounds per sq. in., the pressure being reduced, as before, to approximately 50 pounds in the coking chamber to which the heated vaporous products are supplied, a slightly lower yield of gasoline having an octane number of approximately 72 is produced with an increased yield of gas and approximately the same amount of coke.

The process of this application is disclosed in my companion application, Serial No. 114,182, 15 wherein the process is claimed without limitation to the use of reheated uncondensed gases to assist coking. Apparatus suitable for practicing the process is shown and claimed in my application, Serial No. 190,634.

I claim as my invention:

1. In a process for the pyrolytic conversion of hydrocarbon oils wherein an oil is subjected to an initial cracking operation under sufficient pressure to maintain a substantial portion thereof in liquid phase, the resulting vaporous and residual liquid products separated and the latter subjected to appreciable further vaporization in a zone of substantially reduced pressure relative to that in which they are formed, the improvement which comprises heating regulated quantities of said vaporous conversion products to a higher temperature in a separate cracking zone, whereby to materially improve the antiknock characteristics of their gasoline-like components, introducing resultant highly heated vaporous products into direct contact with the residual liquids undergoing said further vaporization, whereby to effect reduction of the latter to substantially dry coke, separating the resultant vapors into gasoline-like fractions of the desired characteristics, higher boiling components and normally gaseous products and returning a portion of the latter to further treatment in said separate cracking zone. 30

2. A process for the conversion of hydrocarbon oils which comprises subjecting an oil to cracking temperature at superatmospheric pressure in a heating coil and communicating enlarged reaction chamber, separately removing resultant vaporous and liquid conversion products from the reaction chamber, introducing the latter into a zone of substantially reduced pressure, heating vaporous products separately removed from the reaction chamber to an appreciably higher cracking temperature in a separate heating coil, commingling the highly heated products with said residual liquid products supplied to the reduced pressure zone, reducing said residual liquid products in the latter zone to substantially dry coke, 40 subjecting vaporous products from the reduced pressure zone to fractionation for the formation of reflux condensate, returning reflux condensate formed by said fractionation to further cracking in the first mentioned heating coil, subjecting fractionated vapors of the desired end-boiling point to condensation, collecting and separating the resulting distillate and uncondensed gases and returning a portion of the latter to further treatment in said separate heating coil. 50

3. A conversion process which comprises fractionating a mixture of cracked vapors and gases and then subjecting the same to final condensation, separating the final condensate from the uncondensed gases, simultaneously cracking hydro- 70

carbon oil in a cracking zone under sufficient pressure to maintain a substantial portion thereof in liquid phase, separately removing vapors and unvaporized oil from the cracking zone and distilling the latter to coke in a coking zone, heating vapors withdrawn from the cracking zone and a portion of said uncondensed gases to at least the coking temperature of said unvaporized

oil, introducing such heated vapors and gases into contact with the unvaporized oil in the coking zone to assist the coking operation, and supply admixed vapors and gases from the coking zone to the aforesaid fractionating step. 5

JOSEPH G. ALTHER.
